CAR TRUCK

John S. McPherson and Claude L. Orr, Columbus,
Ohio, assignors to The Buckeye Steel Castings
Company, Columbus, Ohio

Application September 23, 1937, Serial No. 165,384

6 Claims. (Cl. 165—195)

This invention relates to improvements in six-wheel trucks and more particularly to improved means for lubricating wear parts.

The primary object of the invention is to provide novel means for lubricating all wearing parts at the connections between the side frame and equalizer members in order to materially reduce the friction and wear between adjacent parts.

With the foregoing object outlined and with 10 other objects in view which will appear as the description proceeds, the invention consists in the novel features hereinafter described in detail in connection with the accompanying drawings and more particularly pointed out in the appended claims.

In the drawings:

Fig. 1 is a side elevation of the medial portion of a six-wheel truck provided with our improvements.

Fig. 2 is a transverse vertical sectional view of a portion of the same taken on the line 2—2 of Fig. 3.

Fig. 3 is a side elevation partly in longitudinal vertical section of a portion of the truck; the 25 section being taken on the line 3—3 of Fig. 2.

Referring to the drawings, 4 designates one of the wheels of a six-wheel truck including equalizer members, one of which is shown in Fig. 1 and designated 5.

As best shown in Figs. 2 and 3, each end of the equalizer member is provided with a pair of upstanding apertured ears 6 having wear plates 7 welded to their inner surfaces. Another wear plate 8 is secured to an arc-shaped portion 9 which is arranged between and is located at the lower ends of the ears. The plate 9 and the ears form a cradle for a supporting block 10 which has a curved bottom surface to slide on the plate 8.

The inner ends of the side frame members 11 rest on the blocks 10 and are positioned between the ears 6, and they are loosely and turnably secured or movably connected to the ears by bolts 11a. Wear plates 12 are welded to opposite sides of the ends of the side frame members and bear against the plates 7.

The operation of our truck requires clearance between the bolts 11a and the holes in the side frames 11 because the side frames must slide 50 slightly on top of the blocks 10. Consequently, clearance is provided about the bolts (see Figs. 2 and 3) to permit movement of the inner ends of the side frames on the blocks 10, and movement of the blocks on the plates 8 without the 55 side frames contacting the bolts 11a. It will

therefore be apparent that the bolts function more as retaining means than as pivotal connections for the side frames and equalizers.

Lubricant pockets or reservoirs 13 are formed integral with the inner ends of the side frame 5 members, and ports 14 lead from the bottoms of the pockets to the bolts. Each pocket is preferably provided with an open upper end.

When waste saturated with lubricating oil is inserted in the pockets, such oil will pass from 10 the pockets through the ducts 14 to the bolts, then along them horizontally in both directions to the wearing surfaces between the plates 7 and 12. The oil passes between these plates by gravity to the bottom of the connections where it 15 lubricates the wearing surface of the blocks 10 and plates 8. In this manner all wear parts at the connections are thoroughly lubricated, thereby reducing the friction and wear between adjacent parts.

While we have disclosed what we now consider to be a preferred embodiment of the invention in such manner that the same may be readily understood by those skilled in the art, we are aware that changes may be made in the details 25 disclosed without departing from the spirit of the invention as expressed in the claims.

What we claim and desire to secure by Letters Patent is:

1. In a six-wheel car truck, an equalizer member provided at each end with a pair of upstanding ears, a wear element carried by each end of said member and each having an arc-shaped concave portion, bearing blocks resting on the wear elements and having arc-shaped bottom surfaces 35 slidably engaging the arc-shaped portions of the wear elements, side frame members having end portions arranged between the ears and slidably resting on said blocks, the inner ends of the side frame members being provided with bolt holes, 40 bolts of materially less diameter than said holes passing through the ears and holes for movably connecting the side frame members to the equalizer member, a reservoir provided on the end portion of each side frame member, ducts leading 45 from the reservoirs to the bolt holes, and contacting wear plates surrounding the bolts and arranged between the ears and the end portions of the side frame members.

2. In an equalizer connection for a railway car 50 truck, a first member provided with upstanding spaced ears and a curved supporting surface between the ears, a supporting block resting on said surface and slidably along the latter, a second member having an end portion extending be- 55

- tween said ears and slidably resting on said block for movement in a substantially horizontal plane, the end portion of the second member having a hole extending therethrough from one ear to the other, an oil reservoir provided on said second member above said hole, a bolt of materially less diameter than said hole passing through said ears and through said hole and connecting said members, the hole being of sufficient size to allow 10 said members to move relatively to one another in a substantially horizontal plane, and a duct leading from the reservoir to said hole.
3. In an equalizer connection for a railway car truck, a first member having spaced projecting 15 ears, a wear element supported by said member and having an arc-shaped concave portion arranged between the ears, a supporting block having a curved bottom surface coinciding with the arc-shaped portion of the element and slidably 20 engaging said concave surface, a second member having an end portion slidably resting on said block for movement relatively to the first member in a substantially horizontal plane, said end portion of the second member having a hole extending 25 therethrough from one ear to the other, means of materially less diameter than said hole, extending through the hole and movably connecting the ears to the end portion of the second member, an oil reservoir provided on the second 30 member above said hole, and a duct for leading lubricant from said reservoir to said hole.
4. In an equalizer connection for a railway car truck, a first member having upstanding projecting ears, a supporting block slidably mounted on 35 said member for movement about a horizontal axis and arranged between said ears, a second member having an end portion arranged between the ears and slidably resting on said block for movement in a substantially horizontal plane relatively to the first member, the end portion of the 40 second member having a hole extending horizontally therethrough from one ear to the other, contacting wear plates arranged between the end portion of the second member and said ears and positioned to receive lubricant discharged from the ends of said hole, means of materially less diameter than said hole, extending through the hole and movably connecting the ears to the end 45
- portion of the second member, an oil reservoir provided on the second member, and a duct leading from the reservoir to said hole.
5. In an equalizer connection for a railway car truck, a first member having spaced upstanding 5 ears, a wear element secured to said member and having a concave curved upper surface arranged between said ears, a bearing block resting on said element and having an arc-shaped lower surface slidably engaging the concave surface of said 10 element, a second member having an end portion arranged between the ears and slidably on said block in a substantially horizontal plane relative to said first member, said end portion of the second member being provided with a bolt hole extending from one ear to the other, a bolt of materially less diameter than said hole passing through the ears and hole for movably connecting 15 said members together, wear plates secured respectively to the ears and to said end portion of the second member and arranged at the ends of the hole between the ears and said end portion of the second member so as to receive lubricant from said hole, an oil reservoir provided on the second member, and a duct leading from the reservoir to said bolt hole.
6. In a six-wheel car truck, an equalizer member provided at each end with a pair of upstanding ears, a wear element carried by each end of said member, each wear element having an arc-shaped concave surface, bearing blocks resting on the wear elements and having arc-shaped bottom surfaces slidably engaging the concave surfaces of the wear elements, side frame members having end portions arranged between the ears and slidably resting on said blocks for movement in a substantially horizontal plane relatively to the equalizer member, each of said end portions of the side frame members being provided with a bolt hole, bolts of materially less diameter than 30 said holes extending through the holes and connecting the side frame members to the equalizer member, a reservoir provided on each of said end portions of the side frame members, and ducts leading from the reservoirs to the bolt holes.
